UNITED STATES PATENT OFFICE

159,891

CRUCIFIX

Joseph A. Chevalier, Aldenville, Chicopee, Mass.

Application September 13, 1948, Serial No. 148,563

Term of patent 7 years

(Cl. D29—23)

To all whom it may concern:

Be it known that I, Joseph A. Chevalier, a citizen of the United States, residing at Aldenville, Chicopee, in the county of Hampden and Commonwealth of Massachusetts, have invented a new, original, and ornamental Design for a Crucifix, of which the following is a specification, reference being had to the accompanying drawing forming part hereof:

Fig. 1 is a front elevational view of a crucifix showing my new design; and

Fig. 2 is a rear elevational view on a reduced scale; and

Fig. 3 is a side elevational view on a reduced scale.

I claim:

The ornamental design for a crucifix, as shown
JOSEPH A. CHEVALIER.
